JUMPING RABBIT TOY

Herschel D. Cruea, Dayton, Ohio

Application June 20, 1957, Serial No. 46,663

Term of patent 14 years

(Cl. D34—15)

FIG -3

FIG -2

Figure 1 is a perspective view of a jumping rabbit toy, showing my new design, the opposite side having substantially the same appearance:

Figure 2 is a side elevational view;

Figure 3 is a top plan view;

Figure 4 is a front elevational view; and

Figure 5 is a rear elevational view.

Portions of the stick have been broken away in the drawing figures for convenience in illustration.

I claim:

The ornamental design for a jumping rabbit toy, as shown and described.
